UNITED STATES PATENT OFFICE

HARRY LEE SPILLMAN, OF WINCHESTER, KENTUCKY, ASSIGNEE OF ONE-HALF TO
RODNEY HAGGARD, OF WINCHESTER, KENTUCKY

BARBER'S TOOL STERILIZER

Application filed September 5, 1930. Serial No. 478,978.

The present invention relates to a sterilizer for tools and the like used by barbers and has for its prime object to provide an exceedingly simple apparatus of this nature which may be manufactured at a low cost, is strong and durable, thoroughly efficient and reliable in use and operation, compact and convenient and otherwise well adapted for the purpose for which it is designed.

With the above and numerous other objects in view as will appear as the description proceeds, the invention resides in certain novel features of construction, and in combination and arrangement of parts as will be hereinafter more fully described and claimed.

In the drawings:—

Figure 1 is a top plan view of the device embodying the features of my invention.

Figure 2 is a longitudinal vertical section therethrough.

Figures 3 and 4 are vertical transverse sections taken substantially on the lines 3—3 and 4—4, respectively, of Figure 1.

Figure 5 is a detail sectional view taken substantially on the line 5—5 of Figure 1.

Referring to the drawings in detail it will be seen that the numeral 5 denotes an oblong container having a top formed across one end thereof as is indicated at 6. A cover 7 is disposed across the remaining portions of the container and is hingedly mounted as is indicated at 8 on one side wall. A tray 9 is formed with a perforated bottom 10 and rests on brackets 11 and a riser 12 in the container 5 to be normally disposed a distance below the lid 7. The riser 12 is of an inverted U-shaped formation having a straight cross member under which extend clips 14 mounted

on the bottom of one end of the tray 9. A chain 15 is engaged with the lid 7 and the other end of the tray 9 so that when the lid 7 is swung to an open position the chain will pick up the last mentioned end of the tray 9 and raise it to a position substantially at the top of the container so that combs, brushes and the like in the tray may be easily removed therefrom or placed therein.

In order to easily operate the lid I provide a lever 16 pivotally mounted on one end of

the container and having a link 17 pivotally engaged therewith and pivotally engaged with the lid 7 as is indicated at 18. It will, therefore, be seen that when the free end of the lever is depressed the lid is swung to an open position and the tray raised to its tilted

position. Elongated transverse slots 20 are formed in the top 6 and have walls 21 depending from the side edges thereof with a slanting bottom 24 carried thereby so that razors and the like may be inserted through the slot to rest on the bottom 24 and dipped in the sterilizing fluid. Aprons 23 depend from openings 22 in the top 6 for the purpose of receiving shears. Another opening 25 is formed on the top and has a cross member 26 so that tweezers may be suspended therefrom through the opening.

It is thought that the construction, utility, operation and advantages of this invention will now be quite apparent to those skilled in this art without a more detailed description thereof.

The present embodiment of the invention has been described in considerable detail merely for the purpose of exemplification since in actual practice it attains the features of advantages enumerated as desirable in the statement of the invention and the above description. It will be apparent that changes in the details of construction, in the combination and arrangement of parts may be resorted to without departing from the spirit and scope of the invention as herein-after claimed or sacrificing any of its advantages.

Having thus described my invention, what I claim as new is:—

1. In a sterilizing apparatus of the class described, a container, an inverted U-shaped member rising from the bottom of the container, a tray, spring clips on one end of the bottom of the tray and engaged with the cross portion of the member, brackets in the container for supporting the other end of the tray, a lid on the container, a chain connecting the lid with the tray remote from the clips, means for swinging the lid to an open position, said lid covering only a portion of

the container, a top across the other portion of the container, said top having elongated slots therein, a substantially triangular shaped plate depending from each side wall of the slot and a bottom forming plate connected to the lower edges of each pair of plates connected with the side walls of each slot with the upper end of the bottom plate connected with an end wall of a slot.

10 2. In a sterilizing apparatus of the class described, a container, an inverted U-shaped member rising from the bottom of the container, a tray, spring clips on one end of the bottom of the tray and engaged with the cross portion of the member, brackets in the container for supporting the other end of the tray, a lid on the container, a chain connecting the lid with the tray remote from the clips, means for swinging the lid to an open position, said lid covering only a portion of the container, a top across the other portion of the container, said top having elongated slots therein extending transversely, a substantially V-shaped plate depending from each side wall of each slot, a bottom forming plate connected to the lower edges of each pair of plates with the upper end of the bottom forming plate connected to an end wall of a slot, said top having an opening 90 therein, an apron depending from said opening and forming continuations thereof.

3. In a sterilizing apparatus of the class described, a container, an inverted U-shaped member rising from the bottom of the container, a tray, spring clips on one end of the bottom of the tray and engaged with the cross portion of the member, brackets in the container for supporting the other end of the tray, a lid on the container, a chain connecting the lid with the tray remote from the clips, means for swinging the lid to an open position, said lid covering only a portion of the container, a top across the other portion of the container, said top having elongated slots therein, substantially triangular shaped plates depending from the side walls of the slots, a bottom forming plate connected to the lower edges of each pair of plates which is connected to the side walls of a slot, 105 said top having holes therein, an apron depending from each hole and forming a continuation thereof, said top also having an opening therein and a cross member extending across the opening and dividing the same into two parts.

4. A sterilizing apparatus of the class described comprising a container having a hinged lid, brackets connected to the interior walls of the container adjacent one end thereof, a cross bar extending across the container an appreciable distance from the brackets, a tray having one end seated on the bracket and its other end adapted to rest on the cross bar, and a spring clip connected 110 with the bottom of the tray for pivotally 115 120 125 130

and removably connecting the tray with the cross bar and a flexible member connecting that end of the tray which engages the bracket with the lid whereby when the lid is raised said end of the tray will be lifted off the bracket. 70

5. In a sterilizer including a casing having a top part, said top part having an elongated slot therein, a substantially triangular shaped plate having one edge connected with each side wall of the slot and depending therefrom, and a bottom forming plate connected to the lower edges of the two plates and having its upper edge connected to an end wall of the slot. 75 80

In testimony whereof I affix my signature.
HARRY LEE SPILLMAN.
